N. W. PLOOSTER

TOY RIDING HORSE

Filed May 23, 1927

*Inventor
Neal W. Plooster*

UNITED STATES PATENT OFFICE.

NEAL W. PLOOSTER, OF ST. PAUL, MINNESOTA.

DESIGN FOR A TOY RIDING HORSE.

Application filed May 23, 1927. Serial No. 22,138. Term of patent 14 years.

To all whom it may concern:

Be it known that I, NEAL W. PLOOSTER, a citizen of the United States, residing at St. Paul, in the county of Ramsey and State of Minnesota, have invented a new, original, and ornamental Design for a Toy Riding Horse, of which the following is a specification, reference being had to the accompanying drawing, forming part thereof.

The figure is a perspective view of a toy riding horse, as shown.

I claim:

The ornamental design for a toy riding horse, as shown.

NEAL W. PLOOSTER.
